WEFT-END CLEARING AND BOBBIN STRIPPING MECHANISM FOR FILLING REPLENISHING LOOMS

Avery C. Kimbirl, Charlotte, N. C., assignor to
The Terrell Machine Company, Charlotte, N. C.,
a corporation of North Carolina

Application May 16, 1931, Serial No. 537,830

19 Claims. (Cl. 139—262)

The invention has relation to mechanisms of the class designed for the removal of waste residues of filling yarns remaining upon bobbins which, by the operation of the filling replenishing instrumentalities of automatic filling replenishing looms, have been expelled from the working shuttles of such looms prior to complete exhaustion of the supplies of filling carried by such bobbins. It also has relation to devices adapted to clear the old, trailing weft-end out of the shuttle-eye, so as to prevent it from being drawn back or otherwise carried into the shed.

The general object of the invention is to provide a practical and efficient mechanism for dealing with the old weft-end during and after its discharge from the lay, both to clear away this weft-end and also to remove it from its bobbin, automatically and without interruption to the working of the loom.

Primarily, my invention consists in a combined clearer and bobbin-stripper mechanism in which a receiver located in a loom in position to receive a bobbin expelled from the working shuttle of the loom, and a winder adapted to engage with a trailing filling-end extending from a bobbin occupying the said receiver to the working shuttle from which it has just been expelled, are so related to each other that the trailing end is caught and drawn out of the shuttle and away from the shed, and thereafter the filling is drawn off from the bobbin lengthwise of the latter without rotation of the bobbin around its longitudinal axis. Obstacles to efficient performance have arisen in practice through failure of the trailing filling-end to become engaged by the rotating winding-off member, and also through the erratic actions of a bobbin rolled or spun on its axis as a result of unwinding its filling tangentially.

The main objects of the present invention are to provide for supporting the ejected bobbin so that its filling may be drawn off from its tip without causing rotation of the bobbin about its axis, and also to provide improved means for insuring the engagement of the trailing filling-end by the rotating member in a bobbin-cleaning attachment of this aforesaid type. These aims are attained in the present novel and improved bobbin-stripping attachment through the provision of means to force the trailing filling-end into contact with the rotating winding-off member, to insure its engagement thereby, and through the provision of a chute into which the expelled bobbin will descend and in which it

will rest with its tip pointing toward the rotating winding-off member. Other objects of the invention have to do with improved operation of the device in general, and will be made plain and their means of accomplishment indicated in the following specification and in the accompanying drawings.

An illustrative embodiment of the invention is shown in the accompanying drawings, in which—

Fig. 1 is a front elevation of certain of the parts at the filling replenishing end of an automatic loom, with the invention applied thereto.

Fig. 2 is a side elevation of the same.

Figs. 3 and 4 are side and end views, respectively, of the winder of the invention.

Figs. 5, 6 and 7 are rear, side, and plan views, respectively, of the bobbin-receiver.

The drawings show only so much of the frame and mechanism of a loom as is useful to indicate the application of the invention. A portion of one side-frame of the loom is represented at 1, a portion of the breast-beam being represented at 2, and a portion of the lay being shown at 3. At 4 is the slot in the bottom of the shuttle-box 5 at the magazine-side of the loom, providing for the passage downward of a bobbin expelled from a working shuttle 6 occupying the said shuttle-box; and at 7 is the apron carried by the lay and by means of which such bobbin is guided forward into the receiver therefor. In prior practice the said receiver is an ordinary catcher-box, into which the bobbin falls from the lay. In the present instance, the loom is provided with a receiver 8 having certain features which will be described. Inasmuch as the change of bobbins that is effected through the replenishing operations takes place when the lay is at front center, the receiver 8 is located in position corresponding with the position of the lay and its apron 7 at front center. It is held in place by supporting brackets 9, 9, attached to end-frame 1. It has an opening in its top, for the admission of a bobbin that is expelled from the working shuttle when such change takes place. A rotary waste-filling winder is shown at 10, mounted upon the end-frame 1 a little to the rear of the path taken by an expelled bobbin in descending from the working shuttle on the lay into the receiver 8. It is shown as comprising a winding-barrel mounted upon a spindle 11 working in a bearing 12 applied to the loom end-frame 1 in such manner that one portion of the spindle projects outward from the end-frame, such portion carrying the winding-barrel, while another portion of the spindle projects inwardly from the end-frame and has fixed

50 55

thereon a band-pulley 13 around which passes a driving-band 14 that passes also around a band-pulley 15 on one of the loom-shafts 16, for instance the bottom or cam-shaft; thus the winding 5 barrel is rotated during the working of the loom, preferably in a clockwise direction as viewed in Fig. 2, so that its uppermost surface is travelling rearward of the loom.

This member 10 is contrived in any suitable or 10 preferred manner capable of engaging and winding onto itself the trailing end of filling extending off from the expelled bobbin and forming the leading end of the wound mass to be removed from such bobbin. The winder 10 is retained on 15 the spindle by a collar 30 applied to the protruding end of the spindle and secured in place by a clamping screw, and is caused to turn in unison with said spindle by a transverse pin 31 fixed in the spindle, and occupying notches 17 20 in the butt of the member 10. This member 10 may be surfaced in any manner desired to increase its tendency to pick up and wrap around itself the end of filling trailing upward from the expelled bobbin; herein, it has a pair of strips 25 32 of felt running throughout its length, and applied to its surface at diametrically opposite points. In between these strips of felt is applied a pair of wooden strips 33, to cooperate with the felt strips in lifting the windings accumulat- 30 ing upon the member 10 away from the latter's surface and to facilitate their removal from time to time, as by cutting. If desired, the member 10 may be given a general taper toward its outward end for the same purpose of aiding removal of 35 waste.

To insure certain and immediate engagement of the trailing end of filling by the winding-off member 24 as the expelled bobbin descends into the receiver 8, and passes in front of the winder 10, 40 novel means are provided comprising a member 41 arranged to lay the trailing end partway around the circumference of the winding-off member 10. This member is contrived to be moved into spaced relation with the winding-off member 10 as the 45 bobbin is expelled, so that said bobbin will descend over the winding-off member, between the latter and the member 41, which latter thereafter is moved into close proximity with the surface of the winding-off member at a point well 50 away from the bobbin as the latter stands at rest in the receiver 8, so that the trailing end is bent around a third or more of the winding-off member's circumference and is laid thereonto in the direction of travel of the surface of the 55 winder, facilitating engagement of the weft-end by such surface. Herein, the end-controlling member 41 is supported parallel to the axis of the member 10 upon an arm 42 upon a rock- 60 shaft 43 supported in bearings 44 at the front 65 of the receiver 8. This rockshaft 43 receives a counter-clockwise movement to raise the member 41 simultaneously with the counter-clockwise rocking of the controller-rockshaft 34 which sets in action the transerrer mechanism which 70 expels the old bobbin, through connections comprising an arm 46 fixed upon the shaft 43, a push-rod 47 pivotally combined with an arm 45, fixed on a transverse rockshaft 21, supported in bearings 22 on the receiver 8 and the loom-side re- 75 spectively. This push-rod 47 slides freely through a swivel 48 on the end of the upper arm 46, and is equipped with an adjustably fixed collar 49 for engagement with the swivel to cause lifting of the member 41 when the controller-rockshaft 34 80 is rocked in counter-clockwise direction. Move-

ment of rockshaft 21 is imparted from the controller-rockshaft through the long arm 35, clamped thereto, by means of the link 38 having one end pivoted to arm 35 and its other end passing through a swivel 39 in the end of an 5 arm 36 fixed on shaft 21, a spring 37 being included to transmit the motion yieldingly in the direction which allows the member 41 to descend over the winder 10, for purposes explained later. Upon the return or clockwise rocking movement 10 of the controller-rockshaft 34, the member 41 gravitates down into proximity to the surface of the winding-off member 10, carrying the trailing end of filling before it into contact with said surface while at the same time it is left free to rise 15 away from the surface of said member 10 to accommodate the accumulation of winding thereon.

By this means, the old trailing weft-end is bent over and part-way around the winder 10 before 20 the shuttle is again picked, and as a result such end is either withdrawn completely from the shuttle-eye as a result of thus lengthening its path of extent and engaging it with the surface of the rotating winder 10, or is held sufficiently securely 25 to prevent its being carried into the shed upon the next pick, and thereafter is wound about the winder 10 and thus disposed of for the time being.

In accordance with the invention as noted hereinbefore, in place of the usual catcher-box there is 30 attached to the loom end-frame 1 the receiver 8 into which the expelled bobbins after passing over the winder 10 descend in such manner as to be supported with their tips pointing upward and rearward. This receiver 8 is of hopper-shape, 35 having a transverse width at its top considerably greater than the length of a bobbin, and an extent of opening in a direction fore-and-aft the loom ample enough to insure the entry of the ejected bobbin therein. Further to direct the de- 40 scending bobbin, the sides are raised to points as indicated at 18, and an overhanging portion 19 applied to the forward sloping edges of such raised sides 18, 18.

The receiver 8 tapers inwardly in both fore- 45 and-aft and transverse directions toward its bottom, to form a relatively narrow chute into which the descending bobbins can only enter substantially endwise. The object of this phase of the invention being to position the ejected bobbins 50 so that the remaining filling thereon may be drawn off over their tips, this chute is disposed slightly off-center when viewed from the front, toward the butt-end of the bobbin as it stands in the working shuttle, to favor the entry of the 55 butt-end of a descending bobbin into the chute, rather than its tip. For the same reason, the side-wall 20 is given as steep a slope as possible, so as not to impede the descent of the bobbin's butt-end, being continued to the very end of the 60 chute, while the opposite side-wall 26 is brought in rather sharply, to intersect the chute well above the latter's lower end, and present a surface against which the bobbin's tip will strike as the bobbin descends in its usual horizontal relation, 65 thus to delay the descent of the tip and turn the bobbin to enter the chute butt-end down. These arrangements are aided by the general tendency of the bobbin to fall with its heavier butt-end first when its travel is impeded by friction result- 70 ing from its incidental contacts with the various surfaces upon the lay and inside the receiver 8, as well as by the drag of its trailing end of filling extending back through the shuttle-eye.

To help bring each ejected bobbin into up- 75

ended position for stripping, the rear wall 27 of the chute is sloped at a considerable angle with respect to vertical, the lower portion of the front wall 28 is correspondingly sloped so that its upper portions overhang its lower edge, and the lower portion 24 of one side-wall is vertical, all with the object of bringing each bobbin in turn to rest against the rear wall 27 of the chute when the lower end of said chute is closed.

10 The bottom of the chute is closed by a door 25 which may be applied in any suitable or desired manner, herein by being attached along its rearward edge to the rockshaft 21 referred to, which extends along the rear edge of the chute and is mounted in the bearing 22 that is combined with the lower end of the chute by screws 23, 23. This door is designed to be opened periodically, as will be explained later, to discharge from the chute each bobbin after it has been stripped, and is 15 preferably disposed on a slant as shown, in order to cooperate with the butt-end of a bobbin to tip the bobbin toward the rear wall 27 of the chute.

20 A feature of the invention having important bearing upon the satisfactory operation of the device is the provision of ample room in cross-section within the chute portion of the receiver 8 to allow the bounding and gyrating expelled bobbin to come promptly to rest standing upon its butt upon the door 25 and with its axis intersecting that of the winding-off member 10 at right angles, which is the most advantageous relation for drawing off the remaining filling, namely over its tip. To provide this ample amount of room, without permitting the bobbin 25 to lie against the rear wall of the chute obliquely, with its tip pointing toward one end or the other of the member 24 instead of at its middle, one or more low partitions 51, preferably V-shaped in section, are disposed in a vertical plane upon 30 said rear wall 16, which cooperates with the side walls to define areas of trough-like character upon the rear wall into which the expelled bobbin will settle and be held in the desired erect relation to the winding-off member 24. The unwinding 35 pull on the upwardly-extending end may also serve to cause an obliquely-disposed bobbin to settle promptly into its trough. A plurality of troughs provides for ample room within the chute for the descending bobbin.

40 As a consequence of the novel mode of operation of the invention in presenting the expelled bobbins with their tip ends pointed to the winding-off means, the filling strips off freely and with little tension from the bobbins, and hence the 45 end is engaged more quickly and certainly by the winding-off member because of its slack condition, insuring the prompt and certain withdrawal of the trailing end from the shuttle-eye. Further, the stripped filling does not wind and 50 pack tightly upon the winding-off member, facilitating its removal therefrom when accumulated in quantity. In addition, as the bobbins are not rotated as hitherto in pulling off the filling therefrom, the resistance to unwinding arising from 55 friction of a revolving bobbin against the surfaces upon which it rests does not occur, and breakage of the filling during stripping is obviated.

60 As is obvious, the construction described comprises means for catching an expelled bobbin and for supporting it in such manner that its remaining weft or filling may be drawn off in the line of its axis over its tip end, and means for engaging the trailing end of filling and for drawing 65 upon said end continually until the entire

length has been transferred from the ejected bobbin to the winding-off member. This stripping or winding-off process takes a material amount of time, not being accomplished instantly, but being ordinarily completed in less time than a fresh bobbin, automatically introduced into the shuttle, would normally spend therein. Hence provision is made for retaining each bobbin in stripping position with the receiver 8 throughout the period in which its successor occupies the working shuttle, and then emptying this stripped bobbin from the receiver, into a catcher-box 60 if desired, simultaneously with the ejection of the said successor from the shuttle, to make way for the stripping of this following bobbin. This is accomplished by connecting the door 25 with the filling-replenishing devices, to open said door to permit the stripped bobbin to fall from the chute, and speedily closing it in time to intercept the falling succeeding bobbin. Thus, the controller-rockshaft 34, which is rocked in a counter-clockwise direction to initiate filling-replenishment, is connected as described to rock the rockshaft 21, so as to open the door 25 and drop out the stripped bobbin supported thereon during the counter-clockwise rocking aforesaid, and to close said door again during the reverse rocking movement. Preferably, means are provided to effect yielding actuation of the door 25 in its closing movement, so that no harm will follow if a bobbin is caught between the door and the end of the chute; thus, the arm 35 pulls the nut on the front end of link 38 positively against the swivel-block 39 on the end of arm 36 to move it in a direction opening the door 25, but communicates reverse movement to said arm 36 through the expanding spiral spring 37 confined between a cotter-pin 40 and the swivel-block 39 which is capable of free sliding movement along pin 38.

40 The provision for unwinding the bobbins from over the tip ends thereof with resulting elimination of any substantial degree of tension and resulting breakage of the yarn during unwinding, coupled with the provision for discharging the stripped bobbin from the receiver before the next one is received therein, so that the succeeding one has the receiver all to itself, eliminates a common disadvantage in prior constructions, in which the broken weft or filling-end from a partly-striped bobbin, or even the empty bobbin itself, sometimes became entangled with a succeeding bobbin while the latter revolved in stripping, resulting in one or more of the bobbins being carried up and lashed fast upon the winding-off member by subsequent lengths of filling wound thereon, with obvious disadvantages.

50 While only one form in which the invention may be embodied is illustrated and described herein, it is obvious that many modifications may be made therein by any person skilled in the art, without departing from the scope of the invention as expressed in the claims. Therefore, the invention is not to be limited to the particular form shown, or to the details of construction thereof, but what is claimed as the invention is:

55 I claim:

60 1. In a weft-replenishing loom, the combination with replenishing mechanism, of a moving surface to engage a trailing weft-end, and means on the loom side-frame and apart from the lay engaging and bending the trailing weft-end around such surface, such means being moved 65 relative to the loom side-frame into engagement

with the weft-end through movement of the replenishing mechanism.

2. In a weft-replenishing loom, the combination with replenishing mechanism, of a moving surface to engage a trailing weft-end, and means actuated by the replenishing mechanism and supported by the loom side-frame apart from the lay engaging and bending the trailing weft-end around such surface, whereby the end of yarn

10 between the moving surface and the shuttle will be engaged with the moving surface and withdrawn from the shuttle-eye.

3. In a weft-replenishing loom, the combination with replenishing mechanism, of a rotating member to engage a trailing weft-end, and means for bending the trailing weft-end around the surface of the rotating member, such means being pivoted on the loom-side forward of the lay and brought into engagement with the weft-end 20 through its movement derived from the replenishing mechanism.

4. In a weft-replenishing loom, the combination with replenishing mechanism, of a rotating member to engage a trailing weft-end, and a normally stationary member on the loom side-frame actuated by the replenishing mechanism and bending the trailing weft-end around the surface of the rotating member through engaging the weft-end between such surface and the 30 lay.

5. In a weft-replenishing loom, the combination with replenishing mechanism of means for withdrawing the trailing weft-end from the shuttle comprising a rotating surface and a member on the loom side-frame and apart from the lay engaging and bending the trailing end around the moving surface and lengthening the path of the trailing end between the bobbin and the shuttle, the member being normally stationary 40 and moved by the replenishing mechanism during the latter's operation.

6. In a weft-replenishing loom, the combination with replenishing mechanism, of a rotating member to draw off a trailing weft-end, and a member swinging about a fixed axis in front of the lay and lay-swords and parallel to that of the rotating member and acting during its swinging movement to engage the weft-end and bear the latter against the rotating member, such 50 members permitting passage of the expelled bobbin between them in its descent.

7. In a weft-carrier-replenishing loom, the combination with replenishing mechanism discarding the spent weft-carrier, of a moving surface on the loom to engage and draw off a trailing weft-end from a discarded weft-carrier, and means for automatically disposing and supporting the discarded weft-carrier during such drawing-off to prevent the weft-carrier from exerting 60 sufficient tension on the trailing and extending therefrom to lift or roll the weft-carrier.

8. In a weft-carrier-replenishing loom, the combination with replenishing mechanism discarding the spent weft-carrier of a moving surface to engage and draw off a trailing weft-end from a discarded weft-carrier, and means for automatically disposing and supporting the discarded weft-carrier during such drawing-off for delivery of the remaining weft thereon from over the tip thereof.

70 9. In a weft-replenishing loom having a lay and a shuttle-box, the combination with replenishing mechanism of means for drawing the trailing weft-end of the expelled spent weft-carrier away from the shuttle-box following replenishment, and

75 a vibrating member operatively independent of

the lay for bringing the trailing end into positive engagement with the drawing-away means, and moved by the replenishing mechanism into engagement with the trailing weft-end for this purpose after replenishment.

10. In a loom, the combination with means for automatically replenishing the working filling-supply and discarding the nearly spent bobbin, of means intercepting the trailing end of filling from the discarded bobbin as the latter is expelled and for drawing off from the discarded bobbin the filling remaining thereon, and means for disposing and supporting the bobbin with its tip toward the drawing-off means throughout the drawing-off of the filling.

11. In a loom, the combination with means for automatically replenishing the working filling-supply, of means for drawing off from the discarded bobbin the filling remaining thereon, and means to receive and support the discarded bobbin 20 and present it to the drawing-off means with its axis substantially in the line of draft.

12. In a loom, the combination with means for automatically replenishing the working filling-supply, of means for drawing off from the discarded bobbin the filling remaining thereon, and a receptacle adapted to receive the discarded bobbin in its fall and bring it to rest with its tip pointed toward the drawing-off means.

13. In a loom, the combination with means for automatically replenishing the working filling-supply and discarding the nearly spent filling-carrier, of means for intercepting the trailing end of filling from the discarded filling-carrier as the latter is expelled and drawing off from the discarded filling-carrier the filling remaining thereon, and means automatically receiving and supporting the filling-carrier in non-rotating relation during such drawing-off of the filling.

14. In a loom, the combination with means for automatically replenishing the working filling-supply and discarding the nearly spent filling-carrier, of means for drawing off from the discarded filling-carrier the filling remaining thereon, means for supporting the filling-carrier to prevent its putting sufficient tension on the trailing end to lift or roll the filling-carrier or break the filling, and means adapted to engage the filling-end trailing behind the filling-carrier as discarded and bring it into engagement with the 50 said drawing-off means.

15. In a loom, the combination with means for automatically replenishing the working filling-supply and expelling the nearly spent filling-carrier with an end thereof trailing behind, of traveling means for drawing off the trailing old filling-end from the filling-carrier, and a member actuated by the replenishing means and having movement in the direction of travel of the drawing-off means so as to engage the trailing filling-end and 60 push it into engagement with the drawing-off means.

16. In a loom, the combination with means for automatically replenishing the working filling-supply, of means for drawing off the trailing old filling-end extending from a discarded filling-carrier, and a normally stationary member moved by the replenishing means into spaced and parallel relation to said drawing-off means to permit the discarded filling-carrier to descend between it and the drawing-off means, and moving into a stationary resting position thereafter to bring the trailing filling-end into contact with said drawing-off means.

17. In a loom, the combination with means for 75

- automatically replenishing the working filling-supply, of means for drawing off the trailing filling-end extending from a discarded filling-carrier, means to receive the discarded filling-carrier 5 and present it to the drawing-off means with its axis substantially in the line of draft, and means actuated through connections with the filling-replenishing means to bring the trailing filling-end into engagement with the drawing-off means.
- 10 18. In a loom, the combination with weft-replenishing mechanism and means for drawing off the trailing weft-end from a discarded weft-carrier, of a receiver for the discarded weft-carrier having a sloping wall and an inclined bottom coacting to dispose the weft-carrier with its tip in elevated relation.
19. In a weft-replenishing loom, in combination, a receiver for the expelled bobbins having a trap-door bottom and inclined walls so related 5 thereto as to stand the expelled bobbin on its butt when resting on such trap-door bottom, devices for stripping the yarn from off the tip of the bobbin without rotating the latter while in this position, a removable container, and means for 10 periodically automatically opening the trap-door to drop the bobbins from the receiver into such container.
